UNITED STATES PATENT OFFICE.

GEORGE RECHTER, OF SAN FRANCISCO, CALIFORNIA.

COMB-CLEANER.

1,339,863.

Specification of Letters Patent. Patented May 11, 1920.

Application filed April 30, 1919. Serial No. 283,728.

To all whom it may concern:

Be it known that I, GEORGE RECHTER, a citizen of the United States, residing at the city and county of San Francisco and State 5 of California, have invented new and useful Improvements in Comb-Cleaners, of which the following is a specification.

This invention relates to a comb cleaner, and particularly to improvements on the 10 structure shown in Patent No. 1,239,964, entitled Comb cleaner, issued to me September 11th, 1917.

One of the objects of the present invention is to provide a cleaner bar especially 15 adapted for combs, said bar being provided with a series of spaced members adapted to pass between the teeth of the comb and movable from an upper position at the base of the teeth to a point near the outer end of 20 the teeth so that stripping or cleaning of the teeth and removal of foreign matter which may have collected therebetween is accomplished. Another object of the invention is to provide means for limiting the movement 25 of the cleaner bar to prevent accidental removal or loss of the same, and furthermore to provide means for locking the cleaner bar against movement when its upper position is assumed. Further objects 30 will hereinafter appear.

The invention consists of the parts and the construction, combination and arrangement of parts as hereinafter more fully described and claimed, having reference to 35 the accompanying drawings, in which—

Figure 1 is a side elevation of the comb showing the application of the cleaner bar.

Fig. 2 is a similar view showing the cleaner bar moved to its lower position.

Fig. 3 is a plan view of the blank from 40 which the cleaner bar is formed.

Fig. 4 is a perspective view of the cleaner bar.

Fig. 5 is an end view of the comb showing 45 the position of the cleaner bar.

Referring to the drawings in detail, A indicates the back of a comb and 2 the teeth. The teeth may be all of the coarse variety or all of the fine, or, as here shown, half 50 fine and half coarse. The comb is provided at its opposite ends with enlarged terminal teeth 3, which teeth are provided near their lower ends with shoulders 4 for the purpose of limiting the downward movement of the 55 cleaner bar as will hereinafter be described.

The cleaner bar generally indicated at 5 is constructed of a single blank of metal (see Fig. 3) which is provided centrally of its length with a plurality of openings 6, between which are formed ribs 7 which are 60 adapted to pass between the teeth of the comb, while the teeth proper extend through the openings 6. The cleaner bar otherwise consists of a pair of side plates 8, on each end of which are formed right-angled ex- 65 tensions 9. These extensions are adapted to be folded upwardly, as shown in Figs. 1, 2 and 5, and each extension is provided with a lateral lip 10, which is bent around the end of the comb to form a pair of shoulders which are adapted to engage the stop 70 shoulders 4 formed on the terminal teeth 3 of the comb. The extensions 9 formed on the side plates 8 are sufficiently long to permit the ribs 7 formed between the side plates 75 to pass downwardly the entire length of the teeth when the bar is depressed, as shown in Fig. 2. The entire length of the teeth may in this manner be scraped and thoroughly cleaned merely by depressing the bar. 80

For the purpose of securing the cleaner bar when in the raised position, shown in Fig. 1, I provide a pair of spring clips 11. These clips are provided with projecting latch members 12 which are adapted to engage recesses 13 formed on each side of the back portion of the comb, thus positively securing the cross bar against being accidentally released or depressed except when manually operated or manipulated. 90

The recesses 13 are short and extend beyond the sides of the short clips 11 to thus allow a pin or the like to be inserted in the recess ends and engaged beneath the clips to unlatch same should this be found necessary, 95 the ends of the latch members 12 being spaced from the clip sides.

In use, it will be apparent that sliding movement of the bar or forcing of the same in a downward direction upon the teeth will 100 cause the ribs to engage the teeth and scrape and remove hair and other foreign matter which may have collected. This may be readily wiped off when removed by the cleaner bar, thereby permitting the bar to 105 be returned to its normal position where it is positively secured by means of the spring clips 11, thus leaving the comb in a clean and sanitary condition.

Having thus described my invention, what 110

I claim and desire to secure by Letters Patent is:

In a comb cleaner, in combination with a comb having a central and relatively short recess formed on each side of the back thereof, a pair of side plates, ribs connecting said plates and formed to extend between the teeth of the comb and a central relatively narrow and short spring clip on each side plate extending outwardly therefrom, said clips having transverse latch members extending thereacross, the ends of

the latch members being spaced from the sides of the clip, and the ends of the recesses extending but a short distance beyond 15 each of the respective sides of the clips.

In testimony whereof I have hereunto set my hand in the presence of two subscribing witnesses.

GEORGE RECHTER.

Witnesses:

JOHN H. HERRING,
W. W. HEALEY.
